DESIGN FOR A FAN

Renaldo C. Epworth, Hackensack, N. J.

Application May 24, 1935, Serial No. 56,997

Term of patent 7 years

To all whom it may concern:

Be it known that I, Renaldo C. Epworth, a citizen of the United States of America, residing at Hackensack, county of Bergen, State of New Jersey, have invented a new, original, and ornamental Design for a Fan, of which the following is a specification, reference being had to the accompanying drawing, forming part thereof.

Fig. 1 is a front elevation of a fan, in open position, showing my new design; and

Fig. 2 is a perspective view of the fan in closed position.

I claim:

The ornamental design for a fan, as shown.

RENALDO C. EPWORTH.
